UNITED STATES PATENT OFFICE

136,731

DESIGN FOR A TOY LOCOMOTIVE

James P. Donahue, Oak Park, Ill.

Application September 15, 1943, Serial No. 111,131

Term of patent 14 years

To all whom it may concern:

Be it known that I, James P. Donahue, a citizen of the United States, residing at Oak Park, in the county of Cook and State of Illinois, have invented a new, original, and ornamental Design for a Toy Locomotive, of which the following is a specification, reference being had to the accompanying drawing, forming a part thereof.

Figure 1 is a perspective view of a toy locomotive showing my new design.

Fig. 2 is a plan view.

Fig. 3 is a side view.

I claim:

The ornamental design for a toy locomotive, substantially as shown.

JAMES P. DONAHUE.
